[57] CLAIM

The ornamental design for an all weather solar dynamo rechargeable radio with torch/lantern/emergency light and siren, as shown and described.

DESCRIPTION

FIG. 1 is a front elevational view of an all weather solar dynamo rechargeable radio with torch/lantern/emergency light and siren showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view with a front part being illustrated in an alternative position;

FIG. 8 is a top plan view with a front part and a crank member being illustrated in an alternative position;

FIG. 9 is a rear perspective view with a front part, a crank member and an antenna being illustrated in an alternative position; and,

FIG. 10 is a rear elevational view with a crank member being illustrated in an alternative position.
